CLAIM

The ornamental design for a portable automotive booster, as shown and described.

DESCRIPTION

FIG. 1 is a perspective view of the portable automotive booster of the invention.

FIG. 2 is a front view of the portable automotive booster depicted in FIG. 1.

FIG. 3 is a rear view of the portable automotive booster depicted in FIG. 1.

FIG. 4 is a top view of the portable automotive booster depicted in FIG. 1.

FIG. 5 is a bottom view of the portable automotive booster depicted in FIG. 1.

FIG. 6 is a left side view of the portable automotive booster depicted in FIG. 1.

FIG. 7 is a right side view of the portable automotive booster depicted in FIG. 1; and,

FIG. 8 is another perspective view of the portable automotive booster depicted in FIG. 1, in an alternate position.
